UNITED STATES PATENT OFFICE

GIUSEPPE CARMELO LARAIA, OF NEW YORK, N. Y.

MECHANICALLY-OPERATED CHAIR OR LIKE DEVICE.

Application filed March 5, 1921. Serial No. 450,043.

To all whom it may concern:

Be it known that I, GIUSEPPE CARMELO LARAIA, a citizen of the United States of America, residing in the borough of Manhattan, city, county, and State of New York, have invented certain new and useful Improvements in Mechanically-Operated Chairs or like Devices, of which the following is a specification.

10 This invention relates to improvements in mechanically operated chairs or similar devices, and is in the nature of an improvement upon the devices disclosed and claimed in my prior Patents Nos. 1,255,321 and 1,255,15 322, issued February 5, 1918.

Although herein disclosed as applied to a barber's chair, the invention is not to be regarded as limited to such particular use, but is equally adapted for application to 20 dental chairs, operating tables, draftsmen's tables, artists' easels and other devices involving supports required to be elevated and lowered and having parts to be shifted to and maintained in different degrees of inclination.

25 More specifically stated, the invention includes improvements in operating mechanism of a device of the above described character, whereby the elevating and depressing means may be operated by and the various locking means controlled by a single operating handle.

It is an important feature of the invention that all parts of the mechanism will 30 always be locked against movement when the controller handle is brought to a normal or neutral position. By moving the handle in one direction, parts of the support are released so that they may be moved to different degrees of inclination, whereby the chair 40 may be shifted from an upright to an inclined position, or vice versa.

On movement of the handle in the opposite direction, a lock which normally prevents 45 rotation or elevation of the chair, is released. Further movement of the controller handle in the same direction, and a reciprocation thereof, is effective to operate hydraulic mechanism adapted to cause the chair to 50 be elevated. Still further movement of the handle beyond the range of reciprocation, for the purpose of elevating, will cause the chair to be lowered.

Improvements in the operating mechanism 55 also include means effective as an aid to the

usual hydraulic elevating means during the raising of the chair, and also effective as buffers or shock absorbers to cushion the chair when lowered.

Another object of the invention is to provide means for effecting accurate adjustments of the various parts of the mechanism, so that they will be properly coordinated to effect their respective functions in their proper predetermined order, in response to the movements of the controller handle.

The invention also includes means to provide for the return of liquid from the plunger surface, and other leakage fluid to the plunger cavity, means for excluding dust and dirt from the liquid reservoir in the plunger, and for concealing unsightly parts of the mechanism and thereby enhancing the appearance of the chair as a whole.

In the drawings illustrating the preferred form of the invention,

Figure 1 is a vertical section through the chair support and parts of the operating mechanism therefor.

Fig. 2 is a vertical section on the line 2-2 of Fig. 1, looking in the direction of the arrows.

Fig. 3 is a vertical section through a part of the mechanism illustrated in Fig. 1 on the line 3-3, looking in the direction of the arrows.

Fig. 4 is a top view of the chair support and enclosed mechanism, parts being broken away and parts illustrated in section.

Fig. 5 is a horizontal section on the line 5-5 of Fig. 1, looking in the direction of the arrows.

Fig. 6 is a side view of the chair and chair support assembled.

Fig. 7 is a side view of a portion of the plunger removed from the cylinder, illustrating an adjusting means for the lock by which rotation and elevation of the chair is normally prevented.

Fig. 8 is a top view of the bearing block, which is an essential element of said lock.

Fig. 9 is a face view of the bearing block illustrated in Fig. 8.

The invention in its preferred form is illustrated as applied to a barber's chair having a seat 20 (Fig. 6) secured to a support 21 having a plunger 22 (Fig. 1), extending downwardly within a cylinder 23, which may be supported by a suitable base 24.

The usual chair back 25 may be pivoted to the seat 20, as at 26, and the usual arm rests 27 may be pivoted at one end 28 to the chair back, and at their other ends 29 to 5 levers 30 pivoted at 31 to the seat 20, and carrying at their ends the usual foot rest 32.

The back 25, arms 27, levers 30 and foot rest 32 may be shifted from the upright position illustrated in Fig. 6, by tilting the 10 back and connected parts to a reclining position, in the usual manner. This shifting of the inclination of the movable parts of the chair may be controlled by a lock bar 33 pivotally connected at one end 34 to the lever 15 30, and normally held in fixed relation with respect to the chair support by the jaws of a clamp 35 (Fig. 1) swiveled in said support.

As a means for controlling the various 20 parts of the chair-operating mechanism, there is provided an operating or controller handle 36 (Figs. 1, 3 and 6) carried by a crank arm 37 at one end of a shaft 38 journaled in the support 21. On moving said handle 36 from its neutral position, as indicated in Fig. 3, in a counterclockwise direction, until the crank axis lies along the line 0—39, a cam 40 will be caused to engage a follower 41 and thereby rotate an arm 42 about a fulcrum bar 43 mounted in the chair support, thus depressing a link 44 terminating in a threaded socket 45 adjustably connected with the threaded end 46 of a link 47 pivoted at its end 48 to a crank 49 mounted fast upon the end of a screw 50 (Fig. 1), in 35 threaded engagement with a nut 51 rotatably mounted in the wall of the plunger 22. Rotation of this nut is normally prevented by means of a screw 52 (Figs. 1 and 7) which engages one of a series of notches or 40 recesses 53 in its periphery. A second screw 54 is threaded in the plunger wall in such position that its shank is clear of the periphery of said nut. The head of said screw, however, extends over the surface of the nut 45 so as to prevent endwise movement thereof. The screw 54 also extends within the plunger to a point lying in the path of the crank 49 (see Figs. 1 and 3), so as to form a limiting stop for said crank.

50 Housed within a recess 55 in the plunger wall at a point concentric with the screw 50, is a bearing block 56 (Figs. 1, 5, 8 and 9) having a cylindrical outer surface conforming with the inner surface of the cylinder 23. 55 This bearing block may be provided with recesses 57 to receive the heads of the screws 52, 54, by which rotation of the block is prevented.

A spring 58 (Figs. 1 and 5), having one 60 end secured to the plunger wall by means of any appropriate fastening devices 59, engages said bearing block at its other end within a slot or recess 60 (Fig. 9) in its face, and normally tends to hold said block clear 65 of the surface of the cylinder.

A spring 61 (Fig. 3), adjustably connected at one end by means of a screw 62 and nut 63 to a support 64 mounted upon the fulcrum bar 43, has its other end secured to the crank 49 and thereby tends to rotate the 70 screw 50 in a clockwise direction, as seen in Fig. 3. This clockwise rotation of the screw 50 advances said screw in the nut 51 and thereby thrusts the bearing block 56 into close contact with the inner surface of the cylinder 23 and maintains it in frictional contact with sufficient force to prevent turning or vertical movement of the plunger relatively to the cylinder.

Movement of the crank axis to the position 0—39, however, as hereinbefore described, causes the screw 50 to be rotated in a counterclockwise direction, as indicated in Fig. 3, thereby permitting the spring 58 to move the block 56 out of contact with the cylinder and permit the support and plunger to be either turned with respect to the cylinder 23, or to be moved vertically with respect thereto.

When the crank is moved to the position 0—39 (Fig. 3) for the above-mentioned purpose, the follower 41 is brought into engagement with a notch 65 in the cam 40, which normally tends to maintain the handle and crank in the last-mentioned position. On further movement of the controller handle in the same direction, the follower 41 is caused to roll along a continuation 66 of the high part of the cam 40 which constitutes a dwell such as to maintain the plunger lock 100 released and ineffective during the further movement of said controller handle for other purposes hereinafter described.

A rough adjustment of the controlling 105 means for the plunger lock may be effective during the assembling of the device by means of the screw connection 45, 46. A finer adjustment of the plunger lock may be effected by first removing the screw 52 and slightly loosening the screw 54, after which the nut 51 may be rotated to effect the desired adjustment, by bringing any one of the recesses 53 in position to be engaged by the screw 52. When the adjustment has been effected the screw 54 will be tightened and the screw 52 110 replaced, thereby firmly maintaining the parts in their adjusted positions.

As a means for elevating and depressing the plunger and parts supported thereby, there is provided (Fig. 2) a pump piston 67 115 pivotally connected at 68 to a plunger 69 having its end in threaded engagement with a socket 70 in a connecting link 71 pivotally connected at 72 to a crank arm 73 extending radially from a sleeve 74 made fast to the shaft 38 by means of a screw or other suitable fastening means 75. The position of the piston 67 within the plunger may be adjusted during the assembling of the mechanism by means of the screw connection be- 120 125 130

tween the pitman 69 and the link 71, and these parts may be firmly held in such adjusted position by means of a lock nut 76.

When the controller handle 36 rests in its 5 normal position (illustrated in Fig. 3), the piston 67 (Figs. 1 and 2) will rest in a normal position in which a by-pass is provided from the part of the plunger cavity below said piston to the part above the same by 10 means of recesses 77 in the inner wall of the plunger.

On moving the controller handle in a counterclockwise direction (Fig. 3) until the 15 crank axis lies along the line 0—39, the pump piston 67 will be lowered to a point slightly below the recesses 77, thereby closing the above-described by-passes, after which a further slight depression of said piston will cause liquid in the plunger cavity to be forced through a check valve 79 (Fig. 1) opening downwardly in the bottom 20 of a lifting piston 80 which closes the lower end of the plunger 22. The liquid forced through the check valve 79 into the part of the cylinder below the lifting piston 80, will 25 impart a slight upward movement to said piston plunger and parts carried thereby.

The liquid used for the above-mentioned 30 purpose may be oil, a mixture of water and glycerine, or any other liquid suitable for such purpose.

On imparting a slight movement to the controller handle 36 in a clockwise direction 35 (Fig. 3), the piston will be slightly raised, causing liquid in the plunger cavity to flow through a check valve 81 in the pump piston to the part of the plunger cavity below the same.

By repeating the reciprocations of the 40 controller handle with the crank between the lines 0—39 and 0—78, more liquid in the plunger cavity will be thus forced into the portion of the cylinder 23 below the piston, and the elevation of the plunger and support 45 may be thus continued to the point desired.

When it is desired to lower the plunger and support, the controller handle 36 is given a further movement in a counterclockwise direction (Fig. 3) somewhat beyond the line 0—78. This movement of the 50 controller handle causes the pump piston 67 to be depressed until its lower portion enters a recess 82 in the inner wall of the plunger which cooperates with recesses 83 in the pump piston to form a by-pass around the same.

On continuing the counterclockwise movement of the controller handle 36, until the crank axis coincides with the line 0—84, 55 the bottom of the pump piston will engage and move one arm of a bell crank 85 (Fig. 2), the other arm of which will be caused to impart lateral movement to a slide valve 86 mounted between guides 87 and the bottom 60 of the lifting piston 80. The slide valve

may be held in close contact with its seat by means of a spring 88 having one end in contact with a slideable bearing block 89 and the other end in engagement with a collar 90 secured to the end of a stem 91 projecting upwardly from said slide valve. A spring 92 (Fig. 2) connected at one end with said slide valve and at its other end to the lifting piston, normally tends to hold the slide valve in its closed position. 75

When the slide valve is moved, however, as a result of the engagement between the pump piston and the bell crank 85, its ports are opened and liquid is permitted to flow back from the lower end of the cylinder 23 80 into the lower end of the plunger cavity, and thence through the by-pass around the pump piston into the space thereabove. By thus permitting the escape of the liquid confined below the lifting piston, the plunger 85 and the support will be permitted to lower until brought to rest by means hereinafter described, or until the controller handle is returned past the line 0—78, so as to permit the slide valve 86 to close. 90

The extreme downward movement of the pump piston 67 to its "support lowering position" may be limited by a stop 92'.

In order to conceal the part of the plunger 22 which is exposed above the end of the cylinder 23 when the support is elevated, there is provided an apron 93 (Figs. 1, 2 and 5), which is caused to move up and down with said support and plunger. There may also be provided a cylindrical shield 94 supported by and extending upwardly from the base 24. If desired, the body portions of the apron and shield may comprise corrugated cylinders, one telescoped within the other, and with the corrugations closely 105 interfitting, as illustrated in Fig. 5, so as to permit relative vertical movement of said apron without impairing the ornamental appearance of the chair base when the support is raised. 110

The means herein disclosed for effecting vertical movements of the apron 93 and at the same time permitting rotation of the support 21 independently of the apron 93, 115 also constitutes auxiliary means which assists the lifting piston 80 during the raising of the support. To this end there are provided auxiliary cylinders 95 (Figs. 2 and 5) extending upwardly from the base 24 to receive auxiliary pistons 96 connected by piston rods 97 passing through cylinder heads 97' and connected with a bearing ring 98 surrounding the upper end of said plunger and forming one element of a raceway for a series of balls 99 maintained in proper relative positions by a roller cage 100, said balls constituting an anti-friction thrust bearing between the support 21 and the bearing ring 98. If desired, the bearing ring 98 may be secured to the ends of the piston rods 97 by 120 125 130

pins or other appropriate fastening means 101.

The apron 93 may be supported at its upper end by means of the bearing ring 98, 5 and may be adjusted and held in fixed relation therewith by means of set screws 102 (Fig. 1) inserted from the inner side of said bearing ring and having outwardly directed ends to engage recesses 103 in the 10 inner surface of said apron.

The auxiliary cylinders 95 are connected with the lower end of the main cylinder 23 by conduits 103' (Fig. 2), so that liquid forced through the check valve in the lifting piston 80 will be effective upon the auxiliary pistons 96 as well as upon said lifting piston and thereby cause the bearing ring 98 to be moved upwardly in accordance with the movements of the plunger, so as to effect 15 an auxiliary upward thrust through the intermediary of the anti-friction bearing 100 to the support.

It will be obvious that the above-described means of support for the apron 93 to cause 20 the same to be moved in exact accordance with the vertical movements of the support, will, at the same time, permit the support to be turned independently of the apron.

To provide for the return of any liquid 25 which may be forced about the pistons 96, as well as the liquid which drains back from the outer surface of the plunger 22, to the liquid reservoir within the plunger, there is provided a groove or channel 104 formed by chamfering the inner, upper edge 30 of the cylinder 23, said channel being connected by passages 105 (Fig. 2) with the upper portions of the auxiliary cylinders 95. These auxiliary cylinders are in turn connected by openings 106 with recesses 107 in 35 the inner wall of the main cylinder 23, and said recesses 107 may be brought into free communication with the liquid reservoir in said plunger at a certain point in the elevation of said plunger by means of a channel 108 in the outer wall of said plunger, which is connected by openings 109 with the recesses 77 in the inner plunger wall.

It will be apparent that when the plunger 40 has been elevated to a point such as to bring the channel 108 in communication with the recesses 107, any liquid in the upper portion of the auxiliary cylinders 95, which may have accumulated to a sufficient extent 45 to overflow the openings 106, will be returned by way of the recesses 107, channel 108, openings 109 and recesses 77 to the liquid reservoir in the plunger.

Should the operative continue to reciprocate the handle 36 until the support and connected parts are elevated to such an extent 50 as to cause the lower surfaces of the auxiliary pistons 96 to be carried slightly above the lower portions of the openings 106, a 55 by-pass would thereby be established,

whereby any further liquid forced through the valve 79 to the lower end of the cylinder 23, would be free to pass through the conduits 103' to the lower ends of the auxiliary cylinders 95, and by way of the openings 106, recesses 107, channels 108, openings 109 and channels 77, to the liquid reservoir in the plunger above the piston. 70

Any further liquid pumped into the lower end of the cylinder 23 would thereby be 75 permitted to escape and be returned to the upper portion of the plunger, and further elevation of the support and its connected parts would thus be prevented.

The passages 105 and recesses 107 are relatively narrow compared with the diameter of the bearing block 56 of the plunger lock, so that the bearing block will not enter the passages or recesses, but will bridge over the same and engage relatively large portions of 80 the cylinder surface. Moreover, the spring 58 will always hold the bearing block free of the cylinder surface whenever the plunger lock is rendered ineffective, so that the edges of the bearing block will not be brought into 85 engagement with the walls of the passages or channels 105, 107, when the chair is rotated while in its elevated position.

In order to prevent the entrance of dust 90 and dirt to the liquid reservoir, the upper end of the support may be tightly sealed by means of a gasket 110 and a backing ring 111, as indicated in Fig. 2.

When so constructed, the support is provided with a valve 112 (Fig. 2) normally 100 held closed by a light spring 113 having one end in engagement with the outer surface of the support, and the other end in engagement with a cap 114 secured to the end of 105 the valve stem and forming a dust protector to prevent, so far as possible, the entrance of dust when the valve is opened.

As a means whereby the valve 112 will be 110 opened during the lowering of the plunger to permit the escape of air as the liquid is caused to flow back into the liquid reservoir, there is provided a loose-link connection 115, 116, between the valve stem and a crank arm 117 carried by the sleeve 74, one 115 link of said connection preferably being a helical spring, as shown.

On rotation of the shaft 38 and sleeve 74 to unlock the plunger, part of the slack in the loose-link connection will be taken up 120 but the valve will not be opened. The slack in the loose-link connection will all be taken up, however, before the handle is moved to the line 0—78 or final pumping position, after which further movement of the handle to its final plunger lowering position will 125 cause said valve 112 to be opened and permit air to escape through channels 118 in said valve stem and 119 in said dust cap.

The spring which constitutes the element 130 116 of the loose-link connection provides for

additional movement of the handle to its plunger lowering position, after the valve has been fully opened, and also serves as a means for automatically returning the handle to its 0-78 position, and for preventing it from being carried beyond that position, by the weight of the piston, if carelessly left between its 0-39 and 0-78 positions. This will prevent the gradual lowering of the piston under the influence of gravity to a sufficient extent to open the slide valve and permit the chair to lower.

1 As a means adapted to assist the above-described hydraulic mechanism during the
15 raising of the support and to act as shock absorbers to cushion the support, when lowered, there are provided a pair of spring buffers which may preferably be supported from the cylinder 23. As illustrated in Fig.
20 1, each of these buffers may comprise a spring 120 coiled about a bar 121 mounted for vertical movement in a spring restraining element 122 herein disclosed as a lug projecting from the outer surface of the cylinder 23. The spring 120 is confined between the spring restraining element 122 and a head 123 on said bar.
25

The above-described buffers are so located with respect to the bearing ring 98 that the heads of the bars 121 will be held in contact with the under surface of said bearing ring. The buffer springs are so designed as to be fully compressed with their coils in contact when the support is in its lowermost position, thereby constituting a limiting stop for said support. During the raising of the support, the upward thrust of the buffer heads upon the bearing ring 98 is transmitted by means of the anti-friction bearing 99, 100, to the support and thereby aids the hydraulic mechanism in lifting the same. During the lowering of the support the springs are gradually compressed, thereby constantly offering greater and greater resistance to the downward movement of the support, so as to serve as shock absorbers to cushion the same at the end of its downward movement.

As the movement of the lock bar 33 which
50 controls the shiftable back and foot rest
is one of rotation as well as reciprocation,
it is essential that the clamp 35 be swiveled
in the support. This clamp, as herein dis-
closed, comprises a swiveled clamping mem-
55 ber 124 (Figs. 1 and 4), within which is
pivoted at 125 a swinging clamping member
126, having an inwardly extending projec-
tion or boss 127 freely movable in a hollow
portion of the member 124. The lock bar
60 33 passes through a lateral opening 128 in
the boss 127, and through oppositely dis-
posed holes in the neighboring walls of the
boss enclosing cavity of the clamping mem-
ber 124, the size and shape of the opening
65 128 being such as to provide for a limited

angular movement of the clamping member 126 about its pivotal connection 125. The lock bar 33 is normally held fast by the frictional engagement therewith of oppositely disposed walls of the opening 128 in the clamping member 126 and of the neighboring holes in the clamping member 124. This normal clamping of the lock bar by the members 124, 126, is effected by means of springs 129, each having one end in engagement with the swinging clamping member and the other end in engagement with the head 130 of a support 131 extending rearwardly from the swiveled clamping member. 70 75 80

As a means for releasing the lock bar 33, when desired, the shaft 38 terminates in a screw 132 (Figs. 1 and 4), in threaded engagement with a nut 133 journaled in the swiveled clamp member 124.

A collar 134 in threaded engagement with the nut 133 cooperates with a flange 135 to prevent undue endwise movement of the swiveled clamping member. The swiveled clamping member 124, nut 133 and collar 134 may be secured in fixed relation, each with respect to the other, by means of set screws 136 in threaded engagement with said collar and having their ends directed towards the swiveled clamping member so as to be adapted to be drawn into firm clamping engagement therewith. 95

The clamp and its releasing means may be accurately adjusted as follows:

With the set screws 136 withdrawn, the nut 133 may be rotated in a direction to advance the screw 132 to its proper relative position with respect to the head 137 of a bearing pin mounted in the swinging clamp member. The collar 134 may then be rotated into close engagement with the adjoining portion of the support. The clamp screws 136 may then be tightened to effect a direct clamping engagement between the collar of the swiveled clamp member and as a result of the reactionary forces at the threaded connection between the collar and nut, these parts will all be firmly maintained in fixed relative positions.

The effect of drawing up the clamping 115 screws 136 after rotating the collar into engaging relation with the adjoining surface of the support, will slightly separate the contacting surfaces between said support and collar, thus providing sufficient play to 120 insure the free rotation of the swiveled bearing member.

A hole 128', in the clamping member 126, which serves as an oil hole and also as a passageway through which a tool may be inserted to remove the bearing pin 137, may be normally closed by a screw plug, as shown in Fig. 1. 125

To facilitate the adjustment of the clamp and its releasing means, the nut 133 and col-

lar 134 may be provided with holes or recesses 138, 139 (Fig. 4) to receive a spanner wrench or other suitable tool.

When it is desired to free the lock bar 33 so as to shift the chair from its upright to its reclined position, or vice versa, the handle 36 is moved in a clockwise direction (Fig. 3), to cause the crank axis 37 to coincide with the line 0—140. This movement 10 of the handle will cause the screw 132 to engage and move the swinging clamp member 126 against the opposing influence of the springs 129, and thereby release the lock bar. The movement of the swinging clamp 15 member 126 may be limited, if desired, by an adjustable stop 140' (Fig. 1), which may also serve as a limiting stop for the movement of the controller handle in its chair clamp releasing direction. On return of 20 the handle 36 to its normal position, clamp member 126 will be again restored by the springs 129 to its normal position, thus causing the lock bar to be again engaged and held fast between parts of the members 124, 25 126.

In order that the shaft 38 may be free to move in an axial direction, as the screw 132 is advanced and withdrawn in the nut 133 to operate the lock bar clamp, without 30 obstruction by or interference with the operating connections between said shaft and other parts of the mechanism, the link 71 is connected to the crank arm 73 by means of lugs spaced somewhat wider than the thickness 35 of said crank arm to provide a clearance space, and the cam 40 is made wider than the follower 41, as best indicated in Figs. 1 and 4.

As a means normally tending to hold the 40 controller handle 36 in its normal position, illustrated in Fig. 3, there is provided a sleeve 141 (Figs. 1 and 4) slidably mounted upon the shaft 38 and having lugs 142 adapted to move in axial direction along said 45 shaft between lugs 143 projecting from the inner surface of the support, the said inter-engaging lugs preventing rotation of the sleeve 141. A spring 144, having its ends confined between one end of the sleeve 141 50 and the inner surface of the support, normally tends to move said sleeve toward the left and thereby cause angular projections or noses 145 (Fig. 4), projecting from the sleeve 74 fixed to said shaft 38 to be held in 55 engagement with recesses or notches 146 in said sleeve 141.

The means last described will normally tend to hold the handle 36 in its neutral position, but, on forcibly turning said handle, 60 the nose 145, cooperating with the inclined surfaces leading into the notches 146, will cause the sleeve 141 to be thrust towards the right and permit further movement of the controller handle and parts operated thereby. 65 It is believed that the operation of the

mechanism as a whole will be apparent in view of the explanation given in connection with the description of its construction. Normally, the controller handle stands in its neutral position and all parts of the mechanism are locked. If it is desired to merely turn or rotate the chair, the controller handle is moved slightly in a counterclockwise direction (Fig. 3), as a result of which the plunger lock will be released and rotation 75 may be effected.

The release of this lock also permits the chair to be elevated. If, therefore, it is desired to elevate the chair, the controller handle is moved somewhat further in a counterclockwise direction (Fig. 3) and reciprocated to operate the pump piston 67. During this raising operation, the auxiliary pistons 96 cooperate with the lifting piston 80 to lift the chair, the apron 93 being correspondingly elevated. This operation is assisted by the buffer springs 120.

When the desired elevation has been attained, the handle may be moved back to its normal position and the plunger lock will again be rendered effective.

If it is desired to move the shiftable parts of the chair to their reclining positions, the controller handle is moved in a clockwise direction (Fig. 3), as a result of which the clamp 35 will release the lock bar 33 and permit the parts of the chair to be adjusted. On rotation of the controller handle back to its neutral position, the clamp will again be rendered effective.

When it is desired to lower the chair, the controller handle is again moved in a counterclockwise direction to the limit of its movement, as a result of which the liquid below the pistons will be permitted to flow 105 back into the liquid reservoir and the chair permitted to move downwardly until brought to rest by the buffer springs 120.

From the foregoing description, it will be seen that the lock bar clamp, which normally prevents movement of the shiftable parts of the chair, and the plunger lock, which normally prevents the turning, elevating or lowering of the chair, are both automatically rendered effective whenever the controller 110 handle is moved to its neutral position. On moving the controller handle in one direction from its neutral position, to advance the screw 132, and thereby release the lock bar clamp, the cam 40 is moved away from 115 the follower 41, and the plunger lock is not affected. On moving the handle in the opposite direction from its neutral position, to cause the cam 40 to engage the follower 41 and cause the plunger to be unlocked, the screw 132 is withdrawn from the clamping member 126, so that the lock bar is not unlocked. In other words, each lock may be independently rendered ineffective by moving the handle in one direction or the other 120 125 130

and each will be again rendered effective on returning the handle to its neutral position.

During the movements of the controller handle between the lines 0—39 and 0—140, to 5 operate the locking mechanisms, the pump piston 67 will be moved; but, because of the by-pass formed by the recess 77, no liquid will be forced through the valve 79 and the plunger 22 will not be elevated.

10 When the controller handle is moved beyond the line 0—39 and reciprocated between the lines 0—39 and 0—78, to elevate the support, and when the handle is moved still farther, to the line 0—84, to permit the chair 15 to lower, the cam follower 41 is caused to ride on the dwell 66, and thereby maintain the plunger lock ineffective so that the plunger is free to move in the cylinder 23.

The lost motion connection between the 20 link 71 and the arm 73 (see Figs. 1 and 4), and the excess width of the cam 40, permits the necessary axial movement of the shaft 38 as the screw 132 is advanced and withdrawn relatively to the nut 133, without interference with or obstruction by other parts 25 of the mechanism.

The various parts of the above-described device are coordinated into one unitary structure, which may be controlled by simple 30 movements of a single controller handle, and may therefore be easily operated by a novice, yet the component parts are all independently adjustable, each with respect to the other, to compensate for wear, so that 35 each may always be caused to perform its function at the proper position of the controller handle.

Although the invention has been herein disclosed as applied to a barber's chair, it is 40 to be understood that it is in no manner limited to such particular application, and that changes and modifications may be made within the scope of the appended claims.

What I claim is:

45 1. In a device of the character described, the combination with a base and a support journaled therein and having shiftable parts adapted to be adjusted to different degrees of inclination, of mechanism for adjusting 50 said support vertically, locking means for preventing change of inclination of said shiftable parts, a second locking means to prevent turning and vertical movements of said support, each of said locking means 55 including automatic holding means normally maintaining its respective locking means effective as a lock, and means for releasing said locking means and for operating said adjusting means comprising a controller 60 handle movable in opposite directions from and returnable to a normal neutral position, means operated by said handle when moved in one direction from said neutral position for releasing said first mentioned locking 65 means, means operated by said handle when

moved in the opposite direction from said neutral position for releasing said second mentioned locking means, by effecting a movement of its parts in opposition to the effort of its holding means, means controlled 70 by said handle for maintaining said second mentioned locking means released against the pressure of its holding means during further movement of said handle in the last mentioned direction, and a connection between said handle and said vertical adjusting mechanism whereby, after such further movement of said handle, said mechanism may be operated thereby to effect the vertical adjustment of said support, said handle and the parts connected therewith, when in their normal neutral positions, being free 75 from and independent of said locking means.

2. In a device of the character described, in combination, a base, a support, hydraulic 80 operating means for elevating and depressing said support relatively to said base, a bearing ring, an anti-friction bearing between said ring and support, and means, comprising a buffer spring, normally held compressed between said base and bearing ring, effective as an aid to said operating means during the elevation of said support, and serving as a shock absorber and limiting 85 stop during the depression thereof. 90

3. In a device of the character described, in combination, a base, a support, operating means for elevating and depressing said support relatively to said base, a bearing ring, means for elevating and depressing 100 said bearing ring in accordance with the vertical movements of said support, an anti-friction bearing between said bearing ring and said support, and means, comprising a buffer spring, normally held compressed between said base and bearing ring, effective 105 as an aid to said operating means during the elevation of said support, and serving as a shock absorber and limiting stop during the depression thereof. 110

4. In a device of the character described, in combination, a base, a support, a cylinder extending upwardly from said base, a plunger extending downwardly from said support, said plunger comprising a piston 115 vertically and rotatably adjustable in said cylinder, an apron vertically movable with said support and adapted to surround and conceal the portion of said plunger exposed above said cylinder, said support being rotatable with respect to said apron, operating means in cooperative relation with said cylinder and piston for elevating and depressing said support and apron with respect to said base, and means for preventing rotation of said apron whereby said support may be rotated independently of said base and apron. 120

5. In a device of the character described, in combination, a base, a support, a cyl- 125

inder extending upwardly from said base, a plunger extending downwardly from said support vertically and rotatably adjustable in said cylinder, a bearing ring, said support being rotatably mounted on said bearing ring, an apron suspended from said bearing ring to surround and conceal the portion of said plunger exposed above said cylinder, operating means for elevating and depressing said ring, support and apron relatively to said base, means for preventing rotation of said apron whereby said support may be rotated independently of said base and apron, and a spring buffer normally held compressed between said base and bearing ring, effective as an aid to said operating means during the elevation of said support and apron and serving as a shock absorber and limiting stop during the depression thereof.

6. In a device of the character described, in combination, a base, a support, a cylinder extending upwardly from said base, a plunger extending downwardly from said support into said cylinder to form a piston, means for forcing liquid into said cylinder beneath said piston to elevate said support, means whereby the liquid may be allowed to escape and permit said support to lower, a bearing ring, an apron suspended therefrom to surround and conceal the portion of said plunger exposed above said cylinder, means independent of said plunger for elevating and lowering said bearing ring and apron in accordance with the corresponding movements of said support but preventing rotation therewith, an anti-friction bearing between said bearing ring and said support, and a buffer comprising springs normally held compressed between said bearing ring and abutments on said cylinder, said buffer being effective as an aid to said means for elevating said support and apron, and serving as a shock absorber and limiting stop during the depression thereof.

7. In a device of the character described, in combination, a base, a support, a cylinder extending upwardly from said base, a plunger extending downwardly from said support into said cylinder to form a piston, means for forcing liquid into said cylinder beneath said piston to elevate said support, means whereby the liquid may be allowed to escape and permit said support to lower, an apron to surround and conceal the portion of said plunger exposed above said cylinder, and means independent of said plunger for elevating and lowering said apron in accordance with the corresponding movements of said support, said support being adapted to turn about a vertical axis with respect to said base and apron.

8. In a device of the character described, in combination, a base, a support, a main cylinder extending upwardly from said base,

a plunger extending downwardly from said support into said cylinder to form a piston, means for forcing liquid into said cylinder beneath said piston to elevate said support, means whereby the liquid may be allowed to escape and permit said support to lower, an apron to surround and conceal the portion of said plunger exposed above said cylinder, a plurality of auxiliary cylinders extending upwardly from said base, and a piston in each of said auxiliary cylinders connected with said apron, said main and auxiliary cylinders being connected beneath said pistons, whereby said apron will be elevated and lowered in accordance with the corresponding movements of said support but may be retained in fixed relation with said base while permitting said support to be turned about a vertical axis.

9. In a device of the character described, in combination, a base, a support, a main cylinder extending upwardly from said base, a plunger extending downwardly from said support into said cylinder to form a piston, means for forcing liquid into said cylinder beneath said piston to elevate said support, means whereby the liquid may be allowed to escape and permit said support to lower, a bearing ring surrounding said plunger, auxiliary cylinders extending upwardly from said base, pistons in said auxiliary cylinders connected with said bearing ring, and an anti-friction bearing between said bearing ring and said support, said main and auxiliary cylinders being connected beneath said piston whereby said bearing ring will be caused to cooperate with said plunger as a means for elevating said support.

10. In a device of the character described, in combination, a base, a support, a main cylinder extending upwardly from said base, a plunger extending downwardly from said support into said cylinder to form a piston, means for forcing liquid into said cylinder beneath said piston to elevate said support, means whereby the liquid may be allowed to escape and permit said support to lower, a bearing ring surrounding said plunger, auxiliary cylinders extending upwardly from said base, pistons in said auxiliary cylinders connected with said bearing ring, an apron supported by said bearing ring and concealing the portion of said plunger exposed above said main cylinder, and an anti-friction bearing between said bearing ring and said support, to facilitate the turning of said support independently of said apron, said main and auxiliary cylinders being connected beneath said piston whereby said bearing ring will be caused to cooperate with said plunger as a means for elevating said support, and constitute means for raising and lowering said apron in accordance with the corresponding movements of said support, but preventing rotation therewith.

11. In a device of the character described, in combination, a base, a support, a cylinder extending upwardly from said base, a hollow plunger extending downwardly from 5 said support into said cylinder to form a lifting piston, means including a pump piston vertically movable in said plunger whereby liquid may be forced from said plunger into the portion of said cylinder 10 beneath said lifting piston and thereby caused to elevate said support, and means for lowering said support comprising a slide valve in said lifting piston, a bell crank lever having one arm in the path of movement 15 of a part of said pump piston and another arm movable into engagement with a part of said slide valve, whereby on depressing said pump piston below the range of its normal pumping stroke, it will rock said bell 20 crank lever and slide said valve, and a stop carried by said plunger to limit the downward movement of said pumping piston and thereby prevent abnormal movement of the parts of said slide valve.
- 25 12. In a device of the character described, in combination, a base, a support, a main cylinder extending upwardly from said base, a hollow plunger extending downwardly from said support into said cylinder to form 30 a lifting piston, means, including a pump piston in said plunger, for forcing liquid from said plunger into the portion of said cylinder beneath said lifting piston to elevate said support, means whereby the liquid 35 may be allowed to flow back into said plunger to permit said support to lower, a plurality of auxiliary cylinders extending upwardly from said base, an auxiliary lifting piston in each of said auxiliary cylinders, 40 said main and auxiliary cylinders being interconnected beneath said pistons whereby all of said pistons may be concomitantly elevated and depressed by the control of said liquid, a groove or channel at the top of said 45 main cylinder formed by chamfering its inner upper edge surrounding said plunger, connections from said channel to the upper portions of said auxiliary cylinders, connections between the upper portions of said 50 auxiliary cylinders and the inner walls of said main cylinder, and interconnected recesses in the outer and inner walls of said plunger near its lower end whereby, on elevating said plunger to a predetermined 55 height, a connection will be established between said auxiliary cylinders and said plunger cavity to permit accumulations of liquid above the pistons in said auxiliary cylinders to flow back into the plunger 60 cavity.
- 65 13. In a device of the character described, in combination, a base, a hollow support, a cylinder projecting upwardly from said base, a hollow plunger projecting downwardly from said cylinder to form a lifting piston, a check valve in said lifting piston, a pump piston in said plunger, operating mechanism in said support and plunger by which said piston may be reciprocated to force liquid from said plunger, 70 through said valve, into the portion of said cylinder beneath said lifting piston, thereby elevating said support, means controlled by a movement of said piston beyond the range of its pumping reciprocation, for allowing 75 said liquid to flow back into said plunger, to permit said support to lower, the hollow support and the portion of said plunger above said pump piston normally forming an air tight chamber, an escape valve normally preventing the escape of air from said chamber, and a loose link connection between said operating mechanism and said escape valve, whereby said operating mechanism may be caused to reciprocate said pumping 80 piston to elevate said support without opening said escape valve, but on further operation to move said piston to its support lowering position, the slack in said loose link valve connection will be taken up and 85 said connection rendered effective to open said escape valve and permit air to escape as the liquid flows back into said plunger.
- 90 14. A device of the character defined in claim 13, having a light spring normally holding the escape valve closed, and in which one element of the loose link valve connection is a spring of sufficient strength to overcome said valve spring and open said valve, said spring link affording means 95 whereby a further movement of the operating means may be effected without further effect on said valve.
- 100 15. In a device of the character described, the combination with a cylinder and a plunger rotatably mounted therein, of means for locking said plunger in said cylinder, said locking means comprising a bearing block housed in a recess in the outer surface of the plunger wall having a face to engage the 105 inner face of said cylinder, a nut journaled in said plunger wall behind said bearing block, a screw in threaded engagement with said nut, said nut being adapted to adjust the position of said screw with respect to 110 said block, means for securing said nut to said plunger in its respective positions of adjustment, and means for turning said screw to locking and unlocking position.
- 115 16. A device of the character defined by claim 15, having a screw threaded in the wall of the plunger, and in which the nut is provided with peripheral recesses, any one of which may be engaged by said screw, whereby said nut may be held in a corresponding one of a number of positions of adjustment.
- 120 17. A device of the character defined by claim 15, having a screw threaded in the wall of the plunger, and in which the nut is pro- 125

- vided with peripheral recesses, any one of which may be engaged by said screw, whereby said nut may be held in a corresponding one of a number of positions of adjustment, 5 the bearing block also having a peripheral recess to be engaged by the head of said screw, thereby preventing rotation of said block and maintaining its axis parallel with the axis of the cylinder.
- 10 18. A device of the character defined by claim 15, having a plurality of screws threaded in the wall of the plunger, and in which the bearing block is provided with recesses to be engaged by the heads of said 15 screws and thereby held against rotation with its axis parallel with the axis of the cylinder, one of said screws being extended inwardly into the path of movement of a part of the operating means to form a limit- 20 ing stop.
19. A device of the character defined by claim 1, having a shaft journaled in the support to form the operating connection between the controller handle and other parts 25 of the operating mechanism, and means, comprising an element having a nose and an element having a notched portion to receive said nose, one of said elements being connected for rotation with said shaft, and the other having a non-rotative connection with 30 said support, for normally holding said handle in its neutral position, said elements being spring pressed one towards the other, whereby said nose is normally maintained 35 in engagement with said notch, but may be forced out of such engagement by the inclined walls of said notch on movement of said handle in either direction from said normal position.
- 40 20. A device of the character defined by claim 1, in which the controlling means for the second-mentioned locking mechanism includes a cam connected with said controller handle, and a follower connected with said locking mechanism, said cam having a recess 45 in its high portion to receive said follower when moved to its lock releasing position, thereby tending to maintain the controller handle in its corresponding position, the remainder of the high portion of said cam 50 forming a dwell to maintain said follower in its lock releasing position on further movement of said handle to control other parts of the operating mechanism.
- 55 21. In a device of the character described, in combination, a support having a part shiftable to different degrees of inclination, a lock-bar to control the movement of said shiftable part, a clamp for said bar, said 60 clamp comprising a block journaled in said support, a clamping member on said block, resilient means for pressing said clamping member in holding relation with said bar, a movable member for operating said clamp, 65 an adjusting member mounted in said block for adjusting the position of said movable member relative to said clamping member, and means for preventing endwise movement of said block in said support, said last-mentioned means comprising a flange on 70 said block preventing endwise movement in one direction, and a collar mounted on said adjusting member for clamping said adjusting member and block in their respective adjusted positions and cooperating with the flange on said block for preventing endwise movement thereof in the opposite direction.
22. In a device of the character described, a support having a part shiftable to different degrees of inclination, a lock bar connected to said shiftable part, a normally effective clamp to control the movements of said lock bar, and means for releasing said clamp, said clamp and clamp releasing means comprising a clamping member swiveled in 85 said support, a nut mounted in said clamping member, a collar on said nut cooperating with a flange on said clamping member as a means to prevent endwise movement thereof, a screw in threaded engagement with said 90 nut, a second clamping member movably mounted in said swiveled clamping member in the path of movement of the end of said screw, said nut being journaled in said swiveled clamping member, and said collar 95 being threaded on said nut whereby said nut may be rotated to adjust the endwise position of said screw relative to said movably mounted clamping member and the end play of said swiveled clamping member relatively to said support may be adjusted by rotating said collar, means for clamping said swiveled clamping member, nut, and collar in fixed relation each with respect to the other, when adjusted, oppositely disposed jaws on 105 said clamping members to embrace and engage said lock bar, resilient means normally tending to hold said movable clamping means in such position as to render said jaws effective, and means for rotating said screw 110 in said nut, thereby shifting the position of said movably mounted clamping means against the effort of said resilient means, so as to render said clamp ineffective upon said lock bar.
- 115 23. A device of the character defined by claim 22, in which the means for clamping the swiveled clamping member, nut, and collar in fixed relative positions of adjustment comprises a plurality of set screws 120 threaded in said collar with their ends directed towards the body portion of said swiveled clamping member, whereby, on drawing up said screws, they will bind said collar and clamping member as a result of 125 their direct engagement therewith, and will at the same time jam the threaded connection between said collar and nut as a result of the reactive forces exerted therebetween.
- 130 24. In a device of the character described,

5 a base, a support, a cylinder extending upwardly from said base, a plunger extending downwardly from said support into said cylinder to form a piston, means for forcing liquid into said cylinder beneath said piston to elevate said support, means whereby the liquid may be allowed to escape and permit said support to lower, a vertically corrugated cylindrical apron surrounding and 10 concealing the portion of said plunger exposed above said cylinder, said support and plunger being free to turn independently of said apron, a vertically corrugated cylindrical shield extending upwardly from said 15 base surrounding and in telescoping relation with said apron, and having vertical corrugations in interfitting relations therewith, and means for causing said apron to move up and down in accordance with the 20 vertical movements of said support but preventing its rotation therewith.

25 In a device of the character described, a base, a support, a cylinder extending upwardly from said base, a hollow plunger extending downwardly from said support, into said cylinder to form a lifting piston, means, including a pump piston in said plunger, for forcing liquid from the plunger cavity into the portion of said cylinder beneath said lifting piston to elevate said support, an external conduit leading from said cylinder, at a point below the lowest portion closed by said plunger when fully depressed, to an intermediate point above that attained 30 by the bottom of said plunger when fully elevated, and a conduit leading from the outer surface of said plunger to the plunger cavity at a point above said pump piston, said conduits, when brought into communication at a predetermined height of said plunger, forming a by-pass about said lifting piston, and thereby preventing further elevation of said support by the operation of said pump piston.

45 26. In a device of the character described, a base, a support, a main cylinder extending upwardly from said base, a hollow plunger extending downwardly from said support into said cylinder to form a lifting piston, means, including a pump piston in said plunger, for forcing liquid from the plunger cavity into the portion of said cylinder beneath said lifting piston to elevate said support, a plurality of auxiliary cylinders extending upwardly from said base, an auxiliary lifting piston in each of said auxiliary cylinders, each connected with said support, said main and auxiliary cylinders being interconnected beneath said pistons whereby all of said pistons may be concomitantly elevated by the liquid forced beneath the same, openings connecting said main and auxiliary cylinders at points normally above said auxiliary pistons, and conduits from the outer surface of said plunger

to the plunger cavity, at points above said pump piston, the outer openings of said conduits being so located as to be in register with the openings connecting said cylinders when the auxiliary pistons are elevated 70 above said openings, whereby a by-pass is established about said lifting piston, thereby preventing further elevation of said support by movements of said pump piston.

27. In a device of the character described, 75 in combination, a base, a support, a cylinder extending upwardly from said base, a plunger extending downwardly from said support into said cylinder to form a piston, means for forcing liquid into said cylinder 80 beneath said piston to elevate said support, means whereby the liquid may be allowed to escape and permit said support to lower, an apron to surround and conceal the portion of said plunger exposed above said cylinder, and means independent of said plunger for elevating and lowering said apron in accordance with the corresponding movements of said support.

28. In a device of the character described, 90 in combination, a base, a support, a cylinder extending upwardly from said base, a plunger extending downwardly from said support into said cylinder to form a piston, means for forcing liquid into said cylinder 95 beneath said piston to elevate said support, means whereby the liquid may be allowed to escape and permit said support to lower, an apron to surround and conceal the portion of said plunger exposed above said cylinder, 100 means independent of said plunger for elevating and lowering said apron in accordance with the corresponding movements of said support, said support being adapted to turn about a vertical axis with respect to 105 said base and apron, and means for preventing relative turning movement of said apron with respect to said base.

29. In a device of the character described, 110 in combination, a base, a support, a main cylinder extending upwardly from said base, a plunger extending downwardly from said support into said cylinder to form a piston, means for forcing liquid into said cylinder beneath said piston to elevate said support, means whereby the liquid may be allowed to escape and permit said support to lower, an apron to surround and conceal the portion of said plunger exposed above said cylinder, a plurality of auxiliary cylinders 115 extending upwardly from said base, and a piston in each of said auxiliary cylinders adapted to support said apron, said main and auxiliary cylinders being connected beneath said pistons, whereby said apron will be elevated and lowered in accordance with the corresponding movements of said support.

30. In a device of the character described, 130 the combination, with a cylinder and a

plunger rotatably mounted therein, of means for locking said plunger in said cylinder, said locking means comprising a bearing block housed in a recess in the outer 5 plunger wall, a screw mounted in said plunger for pressing said block into contact with a surface of said cylinder, and means also mounted in said plunger for adjusting the position of said screw with respect to said block.

31. In a device of the character described, the combination, with a cylinder and a plunger rotatably mounted therein, of means for locking said plunger in said cylinder, said locking means comprising a bearing block housed in a recess in the outer plunger wall, a screw mounted in said plunger for pressing said block into contact with a surface of said cylinder, means 15 mounted in said plunger for adjusting the position of said screw relative to said block, a crank on said screw, an adjustable rod connected with said crank, and means for operating said rod.

32. In a device of the character described, the combination, with a cylinder and a plunger rotatably mounted therein, of means for locking said plunger in said cylinder, and means for releasing said locking means, 30 said locking means comprising a bearing block mounted in said plunger, and having a surface movable into clamping contact with said cylinder, a screw to effect such clamping contact, a crank on said screw, a 35 spring connected with said crank normally tending to turn said screw in its clamp effecting direction, and thereby normally holding said plunger locked in said cylinder, means for adjusting the position of 40 said screw with respect to said block, and means for adjusting the tension of said spring.

33. A device of the character defined by claim 1, having a shaft journaled in the 45 support to form the operating connection between the controller handle and other parts of the operating mechanism, and means in engaging relation with said shaft tending to maintain said handle in its neutral position, said means being adapted to yield and free said shaft on movement of said handle in either direction from said neutral position.

34. A device of the character defined by 55 claim 1, having a shaft journaled in the support to form the operating connection between the controller handle and other parts of the operating mechanism, the means for releasing the second-mentioned locking 60 means and the means for maintaining the same released against the pressure of its holding means during further movement of said handle to control other parts of the mechanism, comprising parts of a member 65 mounted on said shaft.

35. In a device of the character described, the combination with a base and a support, said support being adapted to be adjusted relatively to said base, and having shiftable parts adapted to be independently adjusted, 70 of locking means to hold said elements in different positions of adjustment, lock operating means including a controller handle movable in opposite directions from a neutral position, a shaft mounted in said support and forming the connection between said handle and other parts of said operating means, and holding means comprising a nosed portion and a recessed portion for yieldingly maintaining said shaft and its handle in its neutral position, one of said portions being non-rotative with respect to said support and one being non-rotative with respect to said shaft, said nosed and recessed portions being spring pressed one 80 towards the other whereby they may be caused to engage and hold said handle in its neutral position, said nosed and recessed portions having inclined walls whereby they may be forced out of engagement on movement of said handle in either direction from said neutral position.

36. In a device of the character described, in combination, a support having a part shiftable to different degrees of inclination, 90 a lock bar to control the movement of said shiftable part, a clamp for said bar, said clamp comprising a hollow block journaled in said support, a clamping member pivoted to said block, resilient means tending to 100 maintain said clamping member in holding relation with said bar and means for releasing said clamp, said releasing means comprising a boss on said clamping member projecting into the hollow portion of said block, and a movable member in contact with said boss for moving said clamping member out of clamping position, said boss having a hole 105 through which said bar is adapted to pass, and said hole being radially extended about the pivotal center of said clamping member for permitting a rocking movement thereof.

37. In a device of the character described, in combination, a support having a part shiftable to different degrees of inclination, 110 a lock bar to control the movement of said shiftable part, a clamp for said bar, said clamp comprising a hollow block journaled in said support, a clamping member pivoted 120 to said block, resilient means tending to maintain said clamping member in holding relation with said bar, means for releasing said clamp, said releasing means comprising a boss on said clamping member projecting 125 into the hollow portion of said block, and a movable member in contact with said boss for moving said clamping member out of clamping position, said boss having a hole through which said bar is adapted to pass, 130

and said hole being radially extended about the pivotal center of said clamping member for permitting a rocking movement thereof and means in said block in the path 5 of movement of said boss for limiting the swinging movement of said clamping member.

38. In a device of the character described, in combination, a support having a part 10 shiftable to different degrees of inclination, a lock bar to control the movement of said shiftable part, a clamp for said bar, said clamp comprising a hollow block journaled in said support, a clamping member pivoted 15 to said block, resilient means tending to maintain said clamping member in holding relation with said bar, means for releasing said clamp, said releasing means comprising a boss on said clamping member projecting 20 into the hollow portion of said block, and a movable member in contact with said boss for moving said clamping member out of clamping position, said boss having a hole through which said bar is adapted to pass, 25 and said hole being radially extended about the pivotal center of said clamping member for permitting a rocking movement thereof and an adjustable stop in said block in the path of movement of said boss for limiting 30 the movement of said clamping member.

39. In a device of the character described, in combination, a support having parts shiftable to different degrees of elevation, a lock bar to control the movement of said 35 parts, a clamp for said bar, said clamp comprising a mounting block and a cooperating clamping member, a movable member for operating said clamp, an adjusting member mounted in said block for adjusting 40 the position of said movable member relative to said clamping member, and means for clamping said adjusting member and mounting block in their respective adjusted positions for maintaining the adjustment of said 45 movable member.

40. In a device of the character described, the combination with a cylinder and a plunger movable lengthwise thereof and rotatable with respect thereto, of a bearing block 50 housed in a recess in the outer wall of said plunger and having a face to engage the inner face of said cylinder, means normally pressing said block against the cylinder face to prevent movement of said plunger, operating means to operate said pressing means 55 to release said block and thereby free said plunger, and a resilient means pressing said block to the innermost position in said recess after said block is released from the 60 first-mentioned pressing means.

41. A device of the character defined by claim 1, having a shaft journaled in said support to form the operating connection between the controller handle and the mechanism controlled thereby, the means for re-

leasing said second mentioned locking means, comprising a cam on said shaft, and the means for maintaining said locking means released against the pressure of its holding means during the further movement 70 of said handle to operate other parts of the mechanism to effect the vertical adjustment of said support comprising an extension on said cam.

42. A device of the character defined by 75 claim 1, having a shaft journaled in said support to form the operating connection between the controller handle and the mechanism controlled thereby, said shaft having a threaded connection in said support whereby on movement of said handle in its first mentioned direction said shaft will be moved axially in one direction and thereby caused to release said first mentioned locking means, the means for releasing said second mentioned locking means on movement of said handle in the opposite direction comprising a cam mounted on said shaft and a follower 80 movably mounted in said support, one of said elements having its surface extended laterally to allow for the idle axial movement of said shaft during its rotation to render the cam effective on said follower.

43. In a device of the character described, in combination, a base, a support, a cylinder extending upwardly from said base, a plunger extending downwardly from said support into said cylinder to form a piston, means for forcing liquid into said cylinder beneath said piston to elevate said support, means whereby the liquid may be allowed to escape and permit said support to lower, a bearing ring, an apron suspended therefrom to surround and conceal the portion of said plunger exposed above said cylinder, means 95 independent of said plunger for elevating and lowering said bearing ring and apron in accordance with the corresponding movements of said support, auxiliary supporting means carried by said cylinder, and means 100 comprising a spring buffer normally held compressed between said auxiliary supporting means and said bearing ring, effective as an aid to said means for elevating said support and apron, and serving as a shock absorber and limiting stop during the depression thereof.

44. In a device of the character described, in combination, a base, a support, a main cylinder extending upwardly from said base, a hollow plunger extending downwardly from said support into said main cylinder to form a lifting piston, hydraulic operating means including a pump piston for elevating and depressing said plunger, an externally disposed auxiliary cylinder, a groove or channel at the top of said main cylinder formed by chamfering its inner upper edge surrounding said plunger, a conduit leading from said groove into said aux- 115 120 125 130

ing said screw, said nut constituting means for adjusting said screw relatively to said clamping member, and means for clamping said block and nut in their relative positions of adjustment.

53. In a device of the character described, a support having a part shiftable to different degrees of inclination, a lock bar connected to said shiftable part, a clamp for said bar comprising a flanged block swiveled in said support and a cooperating clamping member movably mounted therein, a nut journaled in said block, a collar having a threaded connection with said nut whereby it may be adjusted to a position relative to said flanged block such as to prevent material endwise movement without preventing rotation, resilient means normally holding said clamping member in clamped relation with said bar, means comprising a rock-shaft having its end threaded in said nut whereby said clamping member may be moved to free said bar, said nut comprising means for adjusting the position of said screw relative to said clamping member, and means for clamping said nut and collar in fixed relation with said mounting block, thereby maintaining the adjustment of said screw.

54. In a device of the character described,

a support having a part shiftable to different degrees of inclination, a lock bar connected to said shiftable part, a clamp for said bar comprising a flanged block swiveled in said support and a cooperating clamping member movably mounted therein, a nut journaled in said block, a collar having a threaded connection with said nut whereby it may be adjusted to a position relative to said flanged block such as to prevent material endwise movement without preventing rotation, resilient means normally holding said clamping member in clamped relation with said bar, means comprising a rock-shaft having its end threaded in said nut whereby said clamping member may be moved to free said bar, said nut comprising means for adjusting the endwise position of said rock-shaft relative to said clamping member, and means for clamping said nut, collar, and block in fixed relation to preserve the adjustment of said screw and the adjustment of the end bearings of the swivel connection between said block and said support.

In witness whereof, I have hereunto signed my name.

GIUSEPPE CARMELO LARAIA.
